UNITED STATES PATENT OFFICE.

LEROY O. STEINKE, OF SPOKANE, WASHINGTON.

COMBINED EXTENSIBLE WRENCH AND PLIERS.

Application filed April 7, 1925. Serial No. 21,433.

To all whom it may concern:

Be it known that I, LEROY O. STEINKE, a citizen of the United States, residing at Spokane, in the county of Spokane and State of Washington, have invented new and useful Improvements in a Combined Extensible Wrench and Pliers, of which the following is a specification.

The object of this invention is to provide a novel and convenient extensible wrench that is also serviceable as and in the capacity of pliers.

The device of my invention involves a casing in which is extensibly disposed a pair of pivotally connected jaw arms carrying jaws on their outer ends that are serviceable as wrench and plier jaws.

In a wrench capacity, I provide novel means for holding the jaws in the desired or necessary longitudinal position in order to obtain the required spread of the jaws.

In a plier capacity, I provide novel means for reducing the spread of the jaws irrespective of their longitudinal adjustment, and in a contracted position of the jaws, longitudinally speaking, I obtain a maximum leverage when the jaws are closed against either something that is to be pulled or turned.

It is also a feature of my invention to provide a device of this character wherein the user can by his thumb, of the wrench gripping hand, freely adjust the jaws longitudinally, and by gripping the wrench, he can with the fingers of the same hand, also contract the jaws.

The device of my invention has many other features which will be more fully described in connection with the accompanying drawing and which will be more particularly pointed out in and by the appended claims.

In the drawing:—

Fig. 1 is a view in side elevation of a combined wrench and pliers illustrative of the preferred form of my invention, with the jaws partly extended;

Fig. 2 is a sectional view showing the jaws retracted;

Fig. 3 is a view similar to Fig. 2, with the jaws extended and illustrating how the device may be used as pliers; and

Fig. 4 is a sectional view on line 4—4 of Fig. 3.

Like characters of reference designate

similar parts throughout the different figures of the drawing.

As shown, my invention includes a casing 1 having relatively narrow side walls 2 and 3, and wide side walls 4. It is a feature of my invention to provide a casing of substantially the same exterior cross-section so that it can the more readily be firmly and uniformly gripped by one hand. For a portion of the length of the casing, wall 2 is recessed on an incline as shown at 5, and is provided with a slot 6 of corresponding length, for a purpose which will presently appear. On the interior of wall 2 is an arm holding tooth 7, and in the opposite wall 3 is a slot 8 to accommodate a lever to be later described. In order to enable me to make the casing all in one piece, I provide wall 2 with an opening 9, to facilitate the attachment of a spring. I make the interior of wall 2, inclined at 10 as shown, to form an abutting wall against which one of the jaw arms may rest when the arms are being contracted.

Reference will next be made to my improved jaw arms and the novel manner in which the latter are adjusted and manipulated.

I employ a pair of jaw arms 11 and 12, which are pivotally connected at their inner ends at 13, and each of which is provided on its outer end with a jaw, as shown at 14 and 15, for use either in a wrench or plier capacity. Means, such as a spring 16, anchored at 17 to arm 12 and having its free end engaging arm 11, serves normally to hold said arms as fully spread as the casing will permit, irrespective of the longitudinal adjustment of said arms in said casing. Arm 11 has a series of notches 18, any one of which may coact with tooth 7 to hold said arms in their longitudinally adjusted position. An adjusting finger grip 19 has a stem 20, extending through slot 6, and threaded or otherwise secured in arm 11. A suitable form of spring 21 is interposed between said grip 19 and the inclined portion 5, and normally holds the arm 11 in the position shown in Fig. 2 against abutment wall 10, and with one of the notches 18 engaged with tooth 7. In order to make the tooth 7 and notches 18 more effective they are made rectangular instead of rounded, so that instead of slipping into and out of retaining engagement, it will be neces-

sary to manually disengage the notches from the tooth. The spring 16 is placed high on the arms so that it will assist in keeping the notched engagement unimpaired.

5 An arm-displacing lever is indicated at 22 and is disposed in slot 8 and pivoted to the casing at 23. I preferably provide a loose pivot by elongating opening 24, so that throughout the major length of lever 22, 10 the latter will engage arm 12 in continuous abutting relation irrespective of the longitudinal adjustment of said arms. By this means I avoid sloppy movement of the pivoted ends of the arms when the jaws are 15 tightened on a nut to be turned, or on a wire that is to be pulled. I provide the lever 22 with a tail-piece 25, against which the free end 26 of a spring, anchored at 27 to the casing, is engaged to normally shift 20 the free end of said lever, and in fact the entire length thereof, toward the interior of the casing and against arm 12.

In view of the fact that the arms 11 and 12 are in all adjustments necessarily in 25 diverging relation, I provide the jaws 14 and 15 with recessed surfaces 28 and 29, which will be substantially parallel in the different adjustments shown, or so nearly so as to be entirely effective.

30 I will next describe the operation of my device.

If it were desired to grip a small nut, and the wrench arms were in the adjustment shown in Fig. 1, the user would press the 35 thumb of his right hand against grip 19, thereby shifting arm 11 to the right and out of engagement with tooth 7. Then the user would retract grip 19 downwardly, as in Fig. 2, until the jaws 14 and 15 substantially 40 fit the nut closely. He would then register the nearest notch 18 with tooth 7, to engage the same, and thus the arms 11 and 12 would be held to the longitudinal adjustment shown in Fig. 2. They could not spread because 45 the casing walls 2 and 3 would prevent such action, and the interposed nut would prevent the jaws from coming closer together. Thus a rigid adjustment would be afforded for wrench service.

50 In this same adjustment shown in Fig. 2, suppose it was desired to grip a wire to pull or extract the same, then the longitudinal adjustment would not have to be changed at all, since by more firmly gripping the casing 1, and hence contracting lever 22 inwardly, arm 12 would be closed against arm 11 and any degree of contraction of the jaws 14 and 15 could easily be obtained. This is equally true, irrespective 55 of the longitudinal position to which the arms are adjusted. In Fig. 3, I have shown the arms adjusted to approximately the same position shown in Fig. 1, and have illustrated the lever 22 forced inwardly to contract the jaws 14 and 15 to a greater extent 60

than in Fig. 1. It will be noted that all four fingers of the right hand will embrace casing 1 abreast of lever 22, and hence the arms on their outer faces will be in flat abutment against wall 10 and lever 22, with no 70 chance to vibrate as regards the lower ends of the arms. This is due in great measure to slot 24, which permits the lever 22 to be moved bodily at both ends toward arm 12. A greater purchase is afforded in the adjustment shown in Fig. 2, when the device is 75 used for pliers, by reason of the low position of pivot 13, as regards arms 12, whereby a much greater leverage is possible.

It is believed that the device of my invention will be fully understood from the foregoing description; and while I have herein shown one specific form of my invention, I do not wish to be limited thereto except for such limitations as the claims may import.

I claim:

1. In a combined extension wrench and pliers, a casing, a pair of pivotally connected jaw arms extensible in said casing whereby different adjustments of said arms can be obtained by extending or retracting said arms with respect to said casing, means normally acting to spread said jaws against said casing, and means mounted on said casing for forcing one of said arms into different degrees of closed relation with respect to the remaining arm irrespective of the extensible adjustment of said arms with respect to said casing.

2. In a combined extension wrench and pliers, a casing having an arm-holding tooth, a pair of pivotally connected jaw arms extensibly disposed in said casing and one arm having a series of notches for coaction with said tooth to retain said arms in various degrees of extensibility, said arms having jaws on their outer ends outside said casing, and means carried by said casing and adapted to act upon the unnotched arm to force the latter toward the notched arm, whereby various degrees of closure of said jaws may be effected in any degree of extensibility of said arms.

3. In a combined wrench and pliers, a casing having an arm-holding tooth on one interior side thereof, an arm-displacing lever pivoted in an opening in that side of said casing opposite to the first-named side thereof, a spring normally urging said lever toward the interior of said casing, a pair of pivotally connected jaw arms extensibly disposed in said casing and having jaws on their outer ends and one of said arms having a series of notches for coaction with said holding tooth, an arm-adjusting finger grip slidable in said casing and connected with said notched arm for extending or retracting said arms to vary the spread of said jaws, the unnotched arm

being adapted to be acted upon by said lever and moved toward said notched arm.

4. In an extensible wrench, a casing having a holding tooth, a pair of pivotally connected jaw arms provided with wrench jaws and being extensibly disposed in said casing, that arm nearest said tooth having a series of notches for selective engagement with said tooth, finger grip means connected 10 with said notched arm and extending slid-

ably through said casing and adapted to be manually actuated to disengage said notched arm from said tooth and extensibly to adjust said arms, and a spring interposed between said means and casing for holding 15 said notched arm in engagement with said tooth.

In testimony that I claim the foregoing as my own, I hereby affix my signature.

LEROY O. STEINKE.
